APPARATUS FOR TREATMENT OF SOFT
BRICK-LIKE GOODS BEFORE BAKING

Herbert Henry Bailey, Kelsall, and James Francis Gill, Liverpool, England, assignors to Autum-tints Brick Machinery Corporation, New York, N. Y., a corporation of New York

Application June 4, 1934, Serial No. 729,014
In Great Britain June 9, 1933

20 Claims. (Cl. 25—1)

The present invention relates to the treatment of green clay, shale or like goods, such as bricks before burning, and more particularly to the treatment of the surfaces of such goods to obtain a so-called rustic effect. The invention relates particularly to machines for obtaining this effect, wherein one or more groups of individual bristles or like means for causing indentation of the surface of the goods are mechanically engaged with and withdrawn from the surface or surfaces of the goods. In conjunction with the action of the said bristles or the like it is usual to supply sand to the surfaces of the goods to be treated in order to obtain suitable colouring effects, the sand being pressed into the surfaces of the goods by the bristles.

For the sake of simplicity in the following description the groups of bristles or the like means for causing indentation of the surface of the goods will be referred to as "brushes".

Machines as set forth above have already been constructed in which three brushes have been arranged to reciprocate rapidly towards and away from a clay column as the clay column is moved relatively to the brushes, and such machines have been found to give excellent results, but the speed of production is limited by the frequency of vibration or reciprocation of the said brushes.

It will be appreciated that should the clay column be displaced relatively to the brushes at an excessive speed in relation to the frequency of the reciprocation of the brushes, then insufficient time would be allowed for entry and withdrawal of the bristles of the brushes into the material of the column, so that appreciable movement of the column would occur, whilst the brushes are in engagement therewith, and the indentations caused by the brushes would thus become blurred and inartistic.

According to the present invention, the brushes are caused or allowed to move in the direction of movement of the clay column at a speed equal to or approximately equal to the speed of the clay column during the time in which they are in engagement with the clay column.

According to another aspect of the invention, the resultant movement of the brushes during the period of their engagement with the clay column includes a component in the direction of movement of the clay column, the value of such component being equal to or approximately equal to the movement of the clay column during such period.

In order to obtain such movement of a brush

in the direction of the clay column, the brush may be actuated by a pair of synchronized eccentrics or preferably by four such eccentrics mounted on parallel shafts arranged at right angles to the direction of movement of the clay column so as to take part in the movement of the eccentrics in the direction of motion of the clay column in addition to the movement in a direction normal to that of the clay column. Thus, during the period of engagement of the brushes with the clay, the brushes are fractionally advanced, and tend momentarily to synchronize in their forward movement with the movement of the clay. Having indented and momentarily travelled with the clay column, the brushes are retracted away from the clay and travelled back in a direction opposite to the movement of the clay to a position ready for recommencing their indenting or puncturing action.

The speed of travel of the clay column may thus be very considerably increased.

Means may be provided for cleaning the brushes during working and mechanical means, such as rotatable cleaning devices, may be provided for effecting this automatically.

In an alternative arrangement, two cams or sets of cams may be provided for actuating the brush, one for moving the brush in the direction of the clay column, and another for moving the brush in a direction normal to the clay column.

Means may be provided for angularly displacing the brush with reference to the clay column between each engagement of the brush with the clay column. The brush may be angularly displaced, for instance, by snubbing means or by a suitable toothed or ratchet gear.

In an alternative arrangement two or more relatively short endless belts having bristles mounted therein may be arranged longitudinally of a clay column so that the bristles of each belt periodically engage and disengage the clay column. Each belt may be mounted on four parallel rollers so arranged that the angle of approach and withdrawal of each belt to the column is small, in order that the bristles may extend almost perpendicularly to the clay when making contact therewith.

In another arrangement, individual bristles may be mounted upon a relatively long endless belt, adapted to be moved towards and away from the clay column and the belt may be driven at a speed equal to or approximately equal to the speed of movement of the clay column.

When the brushes are driven by other means

than contact with the clay, suitable means may be provided for synchronizing the movement of the brushes with the clay column. For instance, the respective parts of a differential mechanism 5 for example, opposite bevels thereof, may be connected respectively with the brush-operating gear, and with an endless belt driving or driven by the clay column, the differential mechanism being adapted to operate a speed control gear, either 10 for the brushes or the clay belt.

For instance in the case of a direct current electric drive an intermediate bevel may be connected with a rheostat control member.

In the case of an alternating current plant the 15 said intermediate bevel may be adapted directly to operate the brush gear of a variable speed induction motor through a differential arm or it may operate such brush gear by means of a pony motor.

20 Suitable gearing may be provided between the clay column and the brush operating gear and the respective bevels of the differential so that when the brushes and the clay are moving in proper synchronism no movement of the intermediate bevel is obtained.

Suitable means may be provided for supplying sand or like material to the clay column before or during engagement of the same with the brush or brushes.

25 30 A particular machine designed according to the present invention includes three relatively long and narrow brushes arranged lengthwise above an endless belt supporting and moving with a clay column, two of the brushes being arranged facing one another, and with their bristles substantially horizontal for operating on the side surfaces of the clay column and the remaining brush being arranged with its bristles substantially vertical for operating upon the upper surface of the clay column.

40 Each brush is mounted on a rigid framework or support which is connected at four rectangularly spaced points to two pairs of synchronized eccentrics, each pair of eccentrics being mounted on a common shaft. Thus each brush-supporting framework may consist of two parallel coupling rods rigidly connected together and attached to the eccentric sheaves.

45 50 The drive is transmitted from a motor to a horizontal main shaft disposed parallel with and midway between the horizontal eccentric shafts of the upper brush, the said eccentric shafts being connected with the main shaft by a pair of relatively short chains operating upon pairs of chain sprockets mounted on said shafts, substantially at the mid-length thereof.

55 60 The side brushes are actuated by pairs of vertical eccentric shafts, one eccentric shaft of each pair being disposed adjacent to the end of one of the horizontal eccentric shafts of the upper brush and being driven from said horizontal eccentric shaft by bevel gearing. Thus bevel gears are mounted at both ends of both horizontal eccentric shafts to mesh with bevel gears which are mounted at the upper ends of the vertical eccentric shafts of the side brushes.

65 70 The pairs of bevel gears are mounted on splines, squares, or the like at the ends of the respective shafts so as to permit longitudinal movement of the bevel gears on said shafts, whilst the pairs of gears are borne in rigid gear housings so as to enable the gears to be maintained correctly in mesh whilst allowing movement of said shafts in a direction perpendicular to their length to adjust the position of the brushes with respect to

75 the clay column. Balance weights may be provided on the eccentric shafts in order as far as possible to ensure smooth running of the machine.

Each pair of eccentric shafts are movably mounted so that the brush and the eccentric shafts as a whole can be displaced towards or away from the clay column to permit adjustment of the initial positions of the brushes. To obtain this result the vertical eccentric shafts are each supported in a slidable footstep bearing and 10 guided by a pair of bearing arms, each of which is slidable in a socket secured to a fixed part of the frame of the machine. Each bearing arm is threaded for engagement with a threaded adjusting spindle, on which is mounted a worm wheel. 15

The two adjusting spindles of each eccentric shaft are oppositely threaded, whilst the worm wheels mesh with a common worm which is mounted on a common shaft with another worm engaging the worm wheels of the adjusting mechanism of the eccentric shaft of the same brush. Thus movement of a single worm shaft may be adapted to cause common displacement of the four bearing arms and of the two eccentric shafts of a brush. The horizontal eccentric shafts of 25 the upper brush are provided with a similar adjusting means, but it is not necessary to provide footstep bearings for the support of these horizontal shafts.

30 Each brush is preferably adapted for angular displacement relatively to the clay column and to achieve this result, each brush is connected to its support at two points, the connection at one point consisting of a pivot pin slidable in the supporting framework, whilst the connection at 35 the other point consists of a pivot pin having an eccentric head mounted in the support and adapted to be rotated by means of a ratchet wheel having radial teeth formed on its outer flat face adapted for engagement with a pawl pivotally 40 mounted on a fixed part of the machine.

It will be appreciated that movement of the brush towards and away from the clay column by reason of the motion of the eccentrics will cause angular displacement of the pawl and 45 movement of the pawl over the teeth of the ratchet wheel to cause rotation of the ratchet wheel and thus angular displacement of the brush.

The brushes are preferably provided with wire 50 bristles which are individually disposed at the corners of equilateral triangles one side of each of which is arranged approximately at 15° to the longitudinal edge of the brush.

55 Preferably the bristles are spaced apart by about $\frac{1}{4}$ " or $\frac{3}{8}$ ". The top brush may advantageously be of about 46" in length and about 10" in width whilst the side brushes may be about the same length but about 4" wide.

One form of machine for carrying the invention into practice is shown by way of example 60 in the accompanying drawings in which:—

Figure 1 is a side elevation taken partly in section along the line I—I of Figure 2.

Figure 2 is a front elevation taken partly in 65 section along the line II—II of Figure 1.

Figure 3 is a plan view, the lower left-hand portion or quadrant of which is taken in section along the line III—III of Figure 2, whilst the lower right-hand quadrant is a section on 70 the line IV—IV of Figure 2.

Figure 4 is a wiring diagram for a speed control gear, whilst Figures 5 and 6 are views of a detail.

The machine is supported by main columns 75

10, 11, 12, 13. Cross members 14, 15 extend between the columns 10, 11 and 12, 13 for the support of longitudinal bearers 16 of a clay belt 17, running over rollers 18, 19.

5 A main drive shaft 20 has mounted thereon sprocket wheels 22, 23 for driving through chains 24, 25, sprockets 26, 27 mounted on horizontal eccentric shafts 28, 29. Vertically disposed eccentric shafts 30, 31, 32, 33 are driven from the 10 ends of said horizontal eccentric shafts 28, 29 by pairs of bevel wheels 34, 35 axially displaceably mounted on the ends of the vertical eccentric shafts and horizontal eccentric shafts respectively. The eccentric shaft ends are squared for 15 engagement in corresponding bores in the bevels.

Bevels are additionally borne by bevel casings 36, whereby the bevels are maintained correctly in mesh irrespective of the eccentric shafts. Each eccentric shaft has fixedly secured thereon 20 a pair of eccentrics 37.

A brush member 38 bearing a number of individual bristles for operation on the upper surface of a clay column moving along the clay belt 17 is supported by a rigid frame member 39, 25 having four rectangularly disposed eccentric straps 40 for engagement with the pairs of eccentrics 37 on the eccentric shafts 28, 29. Similarly, brush members 41, 42 for operating upon the side surfaces of the clay column are supported respectively by rigid frame members 43, 44 each of which has four rectangularly disposed eccentric straps for engagement with the eccentrics 37 on the eccentric shafts 30, 31 and 32, 33 respectively.

35 Each brush 38, 41 or 42 is connected to its frame member by two connections, one connection being a pin-and-slot connection adapted to permit a limited degree of longitudinal movement of the brush relatively to its frame member, 40 whilst the other connection consists of a pin 45 journaled in the frame member, and having an eccentric head 46 engaging the brush, whereby by rotation of the pin will impart a circular displacement to the end of the brush which is connected to the eccentrically headed pin and a longitudinal displacement to the other end of the brush which is connected to the frame member by the pin-and-slot connection.

Thus rotation of the pin 45 will impart to the 50 brush as a whole an angular displacement that is it will cause a variation in the disposition of the brush relatively to the surface of the clay on which it is adapted to act.

Rotation of the pin 45 is caused by means of 55 a wheel 47 having ratchet teeth 48 on the side surface thereof for engagement with a pawl 49 mounted on a fixed pivot 50.

It will be appreciated that movement of the 60 brushes under the influence of the eccentrics 37 will cause periodic angular displacement of the pawl 49 to cause the pawl to engage succeeding teeth on the wheel 47 thereby effecting intermittent angular displacement thereof, and 65 change in angular position of the brush with respect to the clay column.

Each pair of eccentric shafts adapted for operation of a brush is displaceable together with the brush-supporting frame and the brush in a direction normal to the length of the clay column for adjusting the setting of the brushes with respect to the clay column, i. e. for adjusting the average depth to which the bristles of the brushes penetrate the clay column and for 70 adjusting the average distance by which the

brushes are withdrawn from the clay column between each engagement therewith.

To obtain this result each vertical eccentric shaft is supported in a footstep bearing 51 which is slidable in a transverse direction and is borne below and above the eccentrics by bearing arms 52, 53 each of which is slidable in a socket 54, 55.

The sockets 54, 55 are rigidly secured to a fixed vertical frame member 56 which is apertured for the passage therethrough of oppositely threaded adjusting spindles 57, 58 engaging in oppositely threaded openings in the bearing arms 52, 53. The adjusting spindles 57, 58 have fixedly mounted thereon worm wheels 59, 60 which commonly engage one of two worms 61 arranged on a 15 worm shaft 62.

The other worm 61 on the shaft 62 is adapted for operation of worm wheels and adjusting spindles associated with the other eccentric shaft of the pair operating one and the same brush-supporting frame. The worm shaft 62 is adapted to be manually rotated by means of a hand wheel 67.

Thus the worm shaft 62 is adapted for adjustment of the eccentric shafts 32, 33 and the brush 25 62 whilst the worm shaft 63 is adapted for adjustment of the eccentric shafts 30, 31 and the brush 41. The worm shaft 63 is adapted to be manually rotated by means of a hand wheel 68.

The horizontal eccentric shafts 28, 29 are similarly adjusted through a pair of worms 64, 30 mounted on a worm shaft 65 and operating through similar worm wheels, adjusting spindles and bearing arms.

It will be observed that as the bevels 34, 35 35 are mounted in a rigid housing 36 and as the bevels are slidably mounted on the eccentric shafts adjustment of the eccentric shafts in directions normal to their lengths will not upset the meshing of the bevels.

The main drive shaft 20 is supported in bearings 69, 70, 71 and is driven through a belt 72 and belt pulleys 73, 74 by an electric motor 75. A shaft 76 driven through a pair of bevels 77 from the main drive shaft 20 is adapted through a 45 train of bevel gears including pairs of bevels 78, 79, to drive one bevel 80 of a differential gear 81.

The opposite bevel 82 of the differential gear 81 is driven by the pulley 19 of the clay belt 17. 50 The shaft 83 of an intermediate bevel 84, which is adapted to be angularly displaced when the bevels 80, 82 are rotated at different speeds, has mounted thereon a switch contact 85 which is adapted for engagement with successive contact 55 members 86 which are tapped from the field resistance 87 of a direct current dynamo-electric machine.

Figure 4 is a wiring diagram showing the field 60 88 and the field resistance 87 of such a dynamo-electric machine together with the displaceable contact member 85.

The combined velocity ratio of the bevel pairs 78, 79 is so chosen that the bevels 80, 82 of the differential gear 81 rotate at the same speed when 65 the speed of operation of the brushes is exactly appropriate to the speed of the clay belt, that is to say when the average longitudinal component of velocity of the brushes is appropriate to the longitudinal speed of the clay column.

The eccentric shafts are provided with balance weights 66 to assist in the smooth running of the machine.

Suitable hoppers 90 and chutes 91 are shown in chain dotted lines in Figure 2 for supplying 75

sand or like comminuted material to the surfaces of the clay column and the backing plate of the brush 38 is shown in Figure 3 as having slots or openings 89 for permitting the passage of sand through the brush to the clay column.

We declare that what we claim is:—

1. An apparatus for the treatment of soft brick-like goods before baking, comprising a supporting structure including a bed adapted to receive the goods to be treated in column form, means for displacing the goods along said bed, a brush member disposed parallel to one surface of the goods, and having bristles extending substantially normal to the surface of the goods, a pair of eccentric shafts having their axes parallel to said surface of the goods, at least one eccentric on each eccentric shaft and a rigid frame member supporting said brush, and including eccentric straps engaging said eccentrics and means for driving said eccentric shafts.

2. An apparatus for the treatment of soft brick-like goods before baking, comprising a supporting structure including a bed adapted to receive the goods to be treated in column form, means for displacing the goods along said bed, a brush member disposed parallel to one surface of the goods, and having bristles extending substantially normal to the surface of the goods, a pair of eccentric shafts having their axes parallel to said surface of the goods, at least one eccentric on each eccentric shaft and a rigid frame member supporting said brush, and including eccentric straps engaging said eccentrics, means for driving said eccentric shafts, and means for commonly adjusting the spacing of said eccentric shafts, and consequently of the brush from the surface of the goods to be treated.

3. An apparatus for the treatment of soft brick-like goods before baking, comprising a supporting structure including a bed adapted to receive the goods to be treated in column form, means for displacing the goods along said bed, a brush member disposed parallel to one surface of the goods, and having bristles extending substantially normal to the surface of the goods, a pair of eccentric shafts having their axes parallel to said surface of the goods, at least one eccentric on each eccentric shaft and a rigid frame member supporting said brush, and including eccentric straps engaging said eccentrics, means for driving said eccentric shafts, and means for angularly displacing the brush relatively to its supporting frame member about an axis perpendicular to the surface of the goods to be treated.

4. An apparatus for the treatment of soft brick-like goods before baking, comprising a supporting structure including a bed adapted to receive the goods to be treated in column form, means for displacing the goods along said bed, a brush member disposed parallel to one surface of the goods, and having bristles extending substantially normal to the surface of the goods, a pair of eccentric shafts having their axes parallel to said surface of the goods, at least one eccentric on each eccentric shaft and a rigid frame member supporting said brush, and including eccentric straps engaging said eccentrics, means for driving said eccentric shafts, and means for angularly displacing the brush relatively to its supporting frame member about an axis perpendicular to the surface of the goods to be treated, such means being dependent for its operation upon the displacement of the brush-supporting member under the influence of said eccentrics.

5. Apparatus for the treatment of soft brick-like goods before baking comprising a supporting structure, a bed for receiving the goods in column form, means for feeding the goods along said bed, a pair of horizontal eccentric shafts above said bed, a pair of vertical eccentric shafts on each side of said bed, driving means for said eccentric shafts and a brush member operatively connected with each pair of eccentric shafts adapted for displacement into and out of engagement with the goods on rotation of said shafts, such displacement including a component of movement in the direction of movement of the goods at least during engagement of the brush members with the goods.

6. Apparatus for the treatment of soft brick-like goods before baking comprising a supporting structure, a bed for receiving the goods in column form, means for feeding the goods along the bed, a pair of horizontal eccentric shafts above said bed, a pair of vertical eccentric shafts on each side of said bed, driving means for said eccentric shafts, eccentrics on said eccentric shafts, a brush member associated with each pair of eccentric shafts each having a plurality of individual bristles extending at an angle to the surface of the goods, a rigid frame member including eccentric straps connecting each pair of eccentric shafts with one of said brush members whereby rotation of the eccentric shafts imparts a circular movement to the brushes whilst maintaining said angular disposition of the bristles relatively to the goods.

7. Apparatus for the treatment of soft brick-like goods before baking comprising a supporting structure, a bed for receiving the goods in column form, means for feeding the goods along said bed, a pair of horizontal eccentric shafts above said bed, a pair of vertical eccentric shafts on each side of said bed, driving means connected to one pair of eccentric shafts, transmission means between said one pair of eccentric shafts and the other eccentric shafts and a brush member operatively connected with each pair of eccentric shafts adapted for displacement into and out of engagement with the goods on rotation of said shafts, such displacement including a component of movement in the direction of movement of the goods at least during engagement of the brush members with the goods.

8. Apparatus for the treatment of soft brick-like goods before baking comprising a supporting structure, a bed for receiving the goods in column form, means for feeding the goods along said bed, a pair of horizontal eccentric shafts above said bed, a pair of vertical eccentric shafts on each side of said bed, driving means connected to said horizontal eccentric shafts, a bevel gear on each end of each horizontal eccentric shaft, a bevel gear at the upper end of each vertical eccentric shaft engaging a bevel on a horizontal eccentric shaft and a brush member operatively connected with each pair of eccentric shafts adapted for displacement into and out of engagement with the goods on rotation of said shafts, such displacement including a component of movement in the direction of movement of the goods at least during engagement of the brush members with the goods.

9. Apparatus for the treatment of soft brick-like goods before baking comprising a supporting structure, a bed for receiving the goods in column form, means for feeding the goods along said bed, a pair of horizontal eccentric shafts above said bed, a pair of vertical eccentric shafts on

each side of said bed, a brush member operatively connected with each pair of eccentric shafts adapted for displacement into and out of engagement with the goods on rotation of said shafts, such displacement including a component of movement in the direction of movement of the goods at least during engagement of the brush members with the goods, means for displacing said eccentric shafts in pairs towards and away from the bed to adjust the position of the brushes relatively to the bed, driving means connected to said horizontal eccentric shafts, bevel pairs axially displaceably mounted one on the end of a horizontal eccentric shaft and one at the upper end of a vertical eccentric shaft and rigid housings for said bevel pairs to maintain the same in correct mesh.

10. Apparatus for the treatment of soft brick-like goods before baking comprising a supporting structure, a bed for receiving the goods in column form, means for feeding the goods along said bed, a pair of horizontal eccentric shafts above said bed, a pair of vertical eccentric shafts on each side of said bed, driving means for said eccentric shafts, a brush member operatively connected with each pair of eccentric shafts adapted for displacement into and out of engagement with the goods on rotation of said shafts, such displacement including a component of movement in the direction of movement of the goods at least during engagement of the brush members with the goods, and means for angularly displacing the brushes about axes normal to the respective surfaces of the goods upon which they operate.

11. Apparatus for the treatment of soft brick-like goods before baking comprising a supporting structure, a bed for receiving the goods in column form, means for feeding the goods along the bed, a pair of horizontal eccentric shafts above said bed, a pair of vertical eccentric shafts on each side of said bed, driving means for said eccentric shafts, eccentric on said eccentric shafts, a brush member associated with each pair of eccentric shafts each having a plurality of individual bristles extending at an angle to the surface of the goods, a rigid frame member including eccentric straps connecting each pair of eccentric shafts with one of said brush members whereby rotation of the eccentric shafts imparts a circular movement to the brushes whilst maintaining said angular disposition of the bristles relatively to the goods and means for angularly displacing the brushes relatively to said rigid frame members about axes normal to the respective surfaces of the goods upon which they operate.

12. Apparatus for the treatment of soft brick-like goods before baking comprising a supporting structure, a bed for receiving the goods in column form, means for feeding the goods along the bed, a pair of horizontal eccentric shafts above said bed, a pair of vertical eccentric shafts on each side of said bed, driving means for said eccentric shafts, eccentric on said eccentric shafts, a brush member associated with each pair of eccentric shafts each having a plurality of individual bristles extending at an angle to the surface of the goods, a rigid frame member including eccentric straps connecting each pair of eccentric shafts with one of said brush members whereby rotation of the eccentric shafts imparts a circular movement to the brushes whilst maintaining said angular disposition of the bristles relatively to the goods, a pin and slot con-

nnection between each brush and its rigid frame member adjacent one end thereof, an eccentrically headed pin borne by the rigid frame member and engaging the brush adjacent the other end thereof and means for angularly displacing said eccentrically headed pin to vary the angular position of the brushes relatively to the respective surfaces of the goods upon which they operate.

13. Apparatus for the treatment of soft brick-like goods before baking comprising a supporting structure, a bed for receiving the goods in column form, means for feeding the goods along the bed, a pair of horizontal eccentric shafts above said bed, a pair of vertical eccentric shafts on each side of said bed, driving means for said eccentric shafts, eccentric on said eccentric shafts, a brush member associated with each pair of eccentric shafts, each having a plurality of individual bristles extending at an angle to the surface of the goods, a rigid frame member including eccentric straps connecting each pair of eccentric shafts with one of said brush members whereby rotation of the eccentric shafts imparts a circular movement to the brushes whilst maintaining said angular disposition of the bristles relatively to the goods, a pin and slot connection between each brush and its rigid frame member adjacent one end thereof, an eccentrically headed pin borne by the rigid frame member and engaging the brush adjacent the other end thereof, a ratchet wheel on said pin and a pawl mounted on a fixed pivot for engagement with said ratchet wheel to rotate the same on movement of the rigid frame member under the influence of said eccentric shafts.

14. Apparatus for the treatment of soft brick-like goods before baking comprising a supporting structure, a bed for receiving the goods in column form, means for feeding the goods along said bed, a pair of horizontal eccentric shafts above said bed, a pair of vertical eccentric shafts on each side of said bed, driving means for said eccentric shafts, a brush member operatively connected with each pair of eccentric shafts adapted for displacement into and out of engagement with the goods on rotation of said shafts, such displacement including a component of movement in the direction of movement of the goods at least during engagement of the brush members with the goods, socket members rigidly secured to said supporting structure, pairs of internally and oppositely threaded bearing arms engaging each eccentric shaft and each extending into a socket member, a threaded adjusting spindle engaging in each bearing arm, a worm wheel secured to each adjusting spindle, and worm shafts each having two worms thereon each engaging the worm wheels of a pair of adjusting spindles of a pair of eccentric shafts whereby each pair of eccentric shafts and the brush associated therewith may be adjusted as to position relatively to the goods by rotation of said worm shaft.

15. Apparatus for the treatment of soft brick-like goods before baking comprising a supporting structure, a bed for receiving the goods in column form, means for feeding the goods along the bed, a pair of horizontal eccentric shafts above said bed, a pair of vertical eccentric shafts on each side of said bed, driving means for said eccentric shafts, eccentric on said eccentric shafts, a brush member associated with each pair of eccentric shafts each having a plurality of individual bristles extending at an angle to the surface of the goods, a rigid frame member including eccentric straps connecting each pair of ec-

- centric shafts with one of said brush members whereby rotation of the eccentric shafts imparts a circular movement to the brushes whilst maintaining said angular disposition of the bristles relatively to the goods, socket members rigidly secured to said supporting structure, pairs of internally and oppositely threaded bearing arms engaging each eccentric shaft and each extending into a socket member, a threaded adjusting spindle engaging in each bearing arm, a worm wheel secured to each adjusting spindle, and worm shafts each having two worms thereon each engaging the worm wheels of a pair of adjusting spindles of a pair of eccentric shafts whereby each pair of eccentric shafts and the brush associated therewith may be adjusted as to position relatively to the goods by rotation of said worm shaft.
16. Apparatus for the treatment of soft brick-like goods before baking comprising a supporting structure, a bed for receiving the goods in column form, means for feeding the goods along said bed, a pair of horizontal eccentric shafts above said bed, a pair of vertical eccentric shafts on each side of said bed, a main drive shaft, a prime mover for driving said driving shaft, driving means between said main drive shaft and said eccentric shafts, a brush member operatively connected with each pair of eccentric shafts adapted for displacement into and out of engagement with the goods on rotation of said shafts, such displacement including a component of movement in the direction of movement of the goods at least during engagement of the brush members with the goods, and control gear for adjusting the relative speeds of the goods along said bed and the main drive shaft including a differential gear having opposite bevels one driven from the feeding means for the goods and the other driven from said main drive shaft and an intermediate bevel having a spindle extending therefrom for adjusting the speed of said prime mover in the event of a difference in the speed of said opposite bevels.
17. An apparatus for the treatment of soft brick-like goods before baking comprising means for applying comminuted material such as sand to at least one surface of the goods, means for displacing said goods along a given path, a plurality of bristle-like members capable of indent-

ing the surface of the goods on engagement therewith to press said comminuted material into the surface of the goods and means for displacing said bristle-like members so as to impart thereto components of movement towards the goods and in the direction of movement of the goods.

18. An apparatus for the treatment of soft brick-like goods before baking comprising means for applying comminuted material such as sand to at least one surface of the goods, means for displacing said goods along a given path, a plurality of bristle-like members directed substantially normally to the surface of the goods and capable of indenting the surface of the goods on engagement therewith to press said comminuted material into the surface of the goods, and means for displacing said bristle-like members into engagement with the goods, such displacement including a component of movement in the direction of movement of the goods, whilst at the same time maintaining the normal disposition of said bristles relatively to the surface of the goods.

19. An apparatus for the treatment of soft brick-like goods before baking, comprising means for displacing said goods along a given path, a plurality of bristle-like members capable of indenting the surface of the goods on engagement therewith, means for displacing said bristle-like members so as to impart thereto components of movement towards the goods and in the direction of movement of the goods and means for displacing said bristle-like members transversely of the path of the goods between successive indenting movements.

20. An apparatus for the treatment of soft brick-like goods before baking comprising means for displacing said goods along a given path, a group of bristle-like members capable of indenting the surface of the goods on engagement therewith, means for displacing said bristle-like members so as to impart thereto components of movement towards the goods and in the direction of movement of the goods and means for bodily angularly displacing said group of bristle-like members about an axis normal to the surface of the goods.

HERBERT H. BAILEY.
JAMES FRANCIS GILL.
